CLAIM

We claim the ornamental design for a riflescope, as shown and described.

DESCRIPTION

FIG. 1 is a side perspective view of a riflescope of our new design;

FIG. 2 is a right side elevation view of the riflescope of FIG. 1;

FIG. 3 is a left side elevation view of the riflescope of FIG. 1;

FIG. 4 is a top view of the riflescope of FIG. 1;

FIG. 5 is a bottom view of the riflescope of FIG. 1;

FIG. 6 is a front elevation view of the riflescope of FIG. 1; and,

FIG. 7 is a rear elevation view of the riflescope of FIG. 1. The broken lines in FIGS. 1-7 are included for the purpose of illustrating portions of the article and form no part of the claimed design.

1 Claim, 7 Drawing Sheets(56)
